DESIGN FOR A FONT OF DISPLAY LETTERS OF THE ALPHABET

Frank Earl Higgins, New York, N. Y., assignor to California Perfume Company, Inc., New York, N. Y., a corporation of New York

Application August 8, 1936, Serial No. 64,293

Term of patent 14 years

To all whom it may concern:

Be it known that I, Frank Earl Higgins, a citizen of the United States, residing at New York, county and State of New York, have invented a new, original, and ornamental Design for a Font of Display Letters of the Alphabet, of which the following is a specification, reference being had to the accompanying drawing, forming a part thereof.

The drawing shows a face view of a font of display letters of the alphabet illustrating my new design.

I claim:

The ornamental design for a font of display letters of the alphabet as shown.

FRANK EARL HIGGINS.
